UNITED STATES PATENT OFFICE.

GUSTAF H. EKSTROM, OF ROCKFORD, ILLINOIS, ASSIGNOR TO ROCKFORD TOOL COMPANY,
OF ROCKFORD, ILLINOIS, A CORPORATION OF ILLINOIS.

RUBBING-MACHINE.

1,237,491.

Specification of Letters Patent. Patented Aug. 21, 1917.

Application filed December 22, 1916. Serial No. 138,496.

To all whom it may concern:

Be it known that I, GUSTAF H. EKSTROM, a citizen of the United States, residing at Rockford, in the county of Winnebago and 5 State of Illinois, have invented certain new and useful Improvements in Rubbing-Machines, of which the following is a specification.

This invention relates to machines for 10 rubbing or polishing plane surfaces and particularly to portable machines of this class intended for use in rubbing and polishing the varnished surfaces of woodwork.

One of the objects of this invention is to 15 produce a machine of the class described which shall be of sufficiently small and compact construction to permit its use in rubbing and polishing the comparatively narrow depressed surfaces that occur in paneled woodwork.

Another object of the invention is to simplify and cheapen the construction while preserving a high degree of efficiency and durability.

25 In the accompanying drawings Figure 1 is a longitudinal central sectional view of a portable rubbing machine embodying the features of my invention. Fig. 2 is a transverse vertical sectional view taken in the 30 plane of line 2—2 of Fig. 1. Fig. 3 is a section on line 3—3 of Fig. 1. Fig. 4 is a detail view of one of the structural elements of the machine.

The embodiment selected for illustration 35 comprises a body 1 consisting of a tube or shell 2 having caps 3 and 4 screwed upon its ends. The body 1 is adapted to be grasped in the hand of the operator.

Within the body 1 are two power cylinders 40 and two pistons. In the embodiment herein shown, the pistons are relatively stationary and the cylinders reciprocate, the cylinders being rigidly secured together. The cylinders are indicated at 5 and 6. The adjacent 45 ends of the cylinders have heads 7 and 8. If desired, the cylinders 5 and 6 and the heads 7 and 8 may be integral with an intermediate tube 9 which serves to connect the two cylinders rigidly together.

50 The pistons for the cylinders 5 and 6 are indicated at 10 and 11, respectively. These pistons may be secured to the body in any suitable manner. Herein they are shown as having flanged ends 12 which are clamped 55 against the ends of the shell 2 by means of

the caps 3 and 4. The pistons 10 and 11 are herein shown as of sufficient length to serve as effective guides for the cylinders 5 and 6 as the latter reciprocate. It will be noted that the pistons support the cylinders within 60 the body.

The means for supplying pressure fluid, as, for example, compressed air, to the cylinders comprises a rod or stem 13 which may, if desired, be formed integral with the piston 11, as herein shown. The stem 13 projects inwardly from the piston 11 and is axially aligned with the piston. A duct 14 extends axially of the piston 11, the stem 13 and a nipple 15, said nipple being integral 70 with the piston 11 and serving as a connection for a flexible air supply tube (not shown).

In the ends of the tube 9 are secured bushings 16 which are of less internal diameter 75 than the tube 9, the inner ends of the bushings 16 thus forming annular shoulders 17 and 18. The openings through the bushings constitute ports through which pressure fluid flows from the central chamber 9^a of the 80 tube 9 to the cylinders. The inner end portion 19 of the stem 13 is of larger diameter than the remainder of the stem and is adapted to fit snugly within the bushings 16. The length of the portion 19 is greater than the 85 distance between the bushings 16. The duct 14 is arranged to communicate with the central chamber 9^a of the tube 9 by means of two ports 20 and 21. These ports are in different vertical planes as will be evident 90 from Fig. 1, or in other words, the ports are at different points in the length of the portion 19.

The end 22 of the portion 19 co-operates with the annular shoulder 17 to shut off the 95 flow of pressure fluid from the central chamber 9^a to the cylinder 5. The opposite end 23 of the portion 19 serves as a valve co-operating with the annular valve shoulder 18 to shut off the flow of pressure fluid from 100 the chamber 9^a to the cylinder 6.

In the lower sides of the cylinders 5 and 6 are formed exhaust ports 24. In the reciprocation of the cylinders, the pistons 10 and 11 alternately cover and uncover the exhaust 105 ports 24. The air exhausted through the ports 24 escapes to the atmosphere through slots (hereinafter described) in the shell 2.

In the present embodiment, the rubbing element is connected directly to the recip- 110

rotatory structure 5, 6 and 9. Two brackets 25 embrace between them the tube 9 and are rigidly secured together and to said reciprocatory structure. Said brackets project 5 through two parallel slots 26 in the shell 2, as indicated in Figs. 2 and 3. These slots permit the escape of expanded air to the atmosphere. The brackets 25 incidentally prevent relative rotation between the cylinders and the pistons. To the lower ends 10 of the brackets 25 is rigidly secured a wooden block 27 extending parallel with the body 1 and the cylinders 5 and 6. The block 27 may be faced with a strip of rubber 28, as shown. 29 is a strip of felt or other suitable friction material which is secured over the facing 28 by suitable means, as, for example, the nails 30.

Assuming the parts to be in the position 20 shown in Fig. 1, the operation is as follows: Compressed air flows from the duct 14 through the port 21 into the central chamber 9^a and thence into the cylinder 5. The cylinders 5 and 6 are thereby caused to move 25 toward the right. As soon as the shoulder 17 passes the end 22, the flow of air to the cylinder 5 is cut off, but the expansion of the air contained in said cylinder causes continuing right-hand movement of the cylinders. 30 A moment before the shoulder 18 passes the shoulder 23, the exhaust ports 24 for the cylinder 5 are uncovered, thus permitting exhaust of the air from the cylinder 5 to commence. As soon as the shoulder 18 has 35 passed the shoulder 23 compressed air flows from the duct 14 through the port 20 into the central chamber 9^a and thence into the cylinder 6. Therefore, as soon as the momentum of the moving parts can be over- 40 come, the cylinder 6 begins to move toward the left. The supply of compressed air to the cylinder 6 is cut off as soon as the shoulder 18 passes the shoulder 23 in the left-hand movement of the cylinders. The cylinders 45 are thus rapidly reciprocated, carrying with them the rubbing element. The pressure of the air trapped in the cylinders after the exhaust ports 24 are covered by the pistons prevents the heads 7 and 8 from striking the 50 pistons.

In operation, the workman grasps the body 1 and slides the machine over the surface to be rubbed or polished, suitable abrasive or polishing material having been 55 placed upon said surface. While the machine is being thus moved, the cylinders 5 and 6 and the attached pad 29 are rapidly reciprocated to rub or polish the surface against which the workman is pressing the 60 machine.

As will be apparent, the machine herein illustrated and described is of very simple construction and comprises a minimum number of moving parts.

65 The invention herein shown is not limited

to use in small-size machines intended for rubbing small surfaces, but may be employed in the construction of larger machines of the type comprising two rubbing elements, as shown for example, in Patent No. 987,940, 70 dated March 28, 1911. Two machines such as the one herein illustrated, may be connected together end to end, so as to be slid by the operator over the surface to be rubbed, the machines being arranged to reciprocate 75 the pads in opposite directions, and the pads being made of suitable width so as to support the machine on the work in stable equilibrium.

I claim as my invention:

1. A portable rubbing or polishing machine having, in combination, a tubular body, pistons secured to the body within the ends of the body, said pistons being axially aligned, two cylinders slidably supported by said pistons, the adjacent ends of said cylinders having heads, a tube rigidly connecting said heads, said tube having internal annular shoulders near its ends, a stem rigidly connected to one of the pistons and extending axially thereof, the inner end portion of said stem having two annular shoulders adapted to coact with the shoulders in the tube, the distance between the shoulders on the stem being greater 95 than the distance between the shoulders in the tube, said stem and the piston to which it is attached having a pressure-fluid supply duct, which duct communicates with the periphery of the inner end portion of the 100 stem, each of the cylinders having an exhaust port arranged to be covered and uncovered by the adjacent piston in the reciprocation of the cylinders, and rubbing means actuated by the cylinders. 105

2. A portable rubbing or polishing machine having, in combination, a body, pistons secured to the body, two cylinders containing said pistons, the adjacent ends of said cylinders having heads, a tube rigidly connecting said heads, said tube having internal annular shoulders near its ends, a stem rigidly connected to one of the pistons, the inner end portion of said stem having two annular shoulders adapted to 110 coact with the shoulders in the tube, the distance between the shoulders on the stem being greater than the distance between the shoulders in the tube, said stem and the piston to which it is attached having a pressure-fluid supply duct, which duct communicates with the periphery of the inner end portion of the stem, each of the cylinders having an exhaust port arranged to be covered and uncovered by the adjacent piston in the reciprocation of the cylinders, and rubbing means actuated by the cylinders. 115

3. A portable rubbing or polishing machine having, in combination, a body adapt- 120

- ed to be grasped in the hand of the operator, pistons secured to the body within the ends of the body, said pistons being axially alined, two cylinders slidably supported by 5 said pistons, the adjacent ends of said cylinders having heads, a tube rigidly connecting said heads, said tube having internal annular shoulders near its ends, a stem rigidly connected to one of the pistons and 10 extending axially thereof, the inner end portion of said stem having two annular shoulders adapted to coact with the shoulders in the tube, said stem and the piston to which it is attached having a pressure- 15 fluid supply duct, which duct communicates with the periphery of the inner end portion of the stem, exhaust means for the cylinders, and rubbing means actuated by the cylinders.
- 20 4. A portable rubbing or polishing machine having, in combination, a body, pistons secured to the body within the ends of the body, two cylinders containing said pistons, the adjacent ends of said cylinders 25 having heads, a tube rigidly connecting said heads, said tube having internal annular shoulders near its ends, a stem rigidly connected to one of the pistons, the inner end portion of said stem having two annular shoulders adapted to coact with the shoulders in the tube, said stem and the piston 30 to which it is attached having a pressure-fluid supply duct, which duct communicates with the periphery of the inner end portion of the stem, exhaust means for the cylinders, and rubbing means actuated by the cylinders.
- 35 5. A portable rubbing or polishing machine having, in combination, a body, pistons secured to the body, two cylinders containing said pistons, said cylinders having a central chamber moving with the cylinders, said chamber having internal annular shoulders near its ends, a stem rigidly connected to one of the pistons, the inner end portion of said stem having two annular shoulders adapted to coact with the shoulders in the chamber, the distance between the shoulders on the stem being greater than 40 the distance between the shoulders in the chamber, said stem and the piston to which it is attached having a pressure-fluid supply duct, which duct communicates with the periphery of the inner end portion of 45 the stem, each of the cylinders having an exhaust port arranged to be covered and uncovered by the adjacent piston in the reciprocation of the cylinders, and rubbing means actuated by the cylinders.
- 50 6. A portable rubbing or polishing machine having, in combination, relatively stationary pistons, two cylinders containing said pistons, said cylinders having a central chamber moving with the cylinders, said chamber having internal annular shoulders 55 near its ends, a stem rigidly connected to one of the pistons, the inner end portion of said stem having two annular shoulders adapted to coact with the shoulders in the chamber, the distance between the shoulders on the stem being greater than the distance between the shoulders in the chamber, said stem and the piston to which it is attached having a pressure-fluid supply duct, which duct communicates with the periphery of the inner end portion of the stem, each of the cylinders having an exhaust port arranged to be covered and uncovered by the adjacent piston in the reciprocation of the cylinders, and rubbing means actuated by the cylinders.
- 60 7. A portable rubbing or polishing machine having, in combination, a pair of cylinders rigidly connected together, a pair of pistons for the cylinders, said pistons being rigidly connected together, a rubbing element rigidly connected to one of said pairs of elements, said cylinders having a central chamber, said chamber having internal annular shoulders near its ends, a stem rigidly connected to one of the pistons, the inner end portion of said stem having two annular shoulders adapted to coact with the shoulders in the chamber, the distance between the shoulders on the stem being greater than the distance between the shoulders in the chamber, said stem having a duct arranged for communication with a source of pressure fluid, which duct communicates with the periphery of the inner end portion of the stem, exhaust means for the cylinders, and rubbing means actuated by the cylinders.
- 65 8. A portable rubbing or polishing machine having, in combination, relatively stationary pistons, two cylinders containing said pistons, said cylinders having a central chamber moving with the cylinders, said chamber having internal annular shoulders near its ends, a relatively stationary stem having two annular shoulders adapted to coact with the shoulders in the chamber, the distance between the shoulders on the stem being greater than the distance between the shoulders in the chamber, said stem having a duct arranged for communication with a source of pressure fluid, which duct communicates with the periphery of the stem between the shoulders on the stem, exhaust means for the cylinders, and rubbing means actuated by the cylinders.
- 70 9. A portable rubbing or polishing machine having, in combination, a pair of cylinders rigidly connected together, a pair of pistons for the cylinders, said pistons being rigidly connected together, rubbing means actuated by one of said pairs of elements, said cylinders having a central chamber, said chamber having internal annular shoulders near its ends, a stem rigidly connected to one of said pairs of elements, said stem having two annular shoulders adapt-

ed to coat with the shoulders in the chamber, said stem having a pressure-fluid supply duct arranged for communication with a source of pressure-fluid supply and also communicating with the periphery of the stem between the shoulders on the stem, and exhaust means for the cylinders.

10. A portable rubbing or polishing machine having, in combination, relatively stationary pistons, two cylinders containing said pistons, said cylinders having a central chamber moving with the cylinders, said chamber having valve means, coöperating valve means attached to one of the 15 pistons, means for supplying pressure-fluid to said chamber, exhaust means for the cylinders, and rubbing means actuated by the cylinders.

11. A portable rubbing or polishing machine having, in combination, a pair of cylinders rigidly connected together, a pair of pistons for the cylinders, said pistons being rigidly connected together, rubbing means actuated by one of said pairs of elements, there being a chamber between said cylinders, said chamber having internal annular shoulders near its ends, a stem connected to one of said pairs of elements and having two annular shoulders adapted to 25 30 coat with the shoulders in the chamber, said stem having a pressure-fluid supply duct arranged for communication with a source of pressure-fluid supply and also communicating with the periphery of the

stem between the shoulders on the stem, 35 and exhaust means for the cylinders.

12. A portable rubbing or polishing machine having, in combination, a pair of cylinders rigidly connected together, a pair of pistons for the cylinders, said pistons 40 being rigidly connected together, rubbing means actuated by one of said pairs of elements, said pairs of elements being held against relative rotation, there being a chamber between said cylinders, said chamber having annular valve means, coöperating annular valve means connected to one of said pairs of elements, means for supplying pressure-fluid to the chamber, and exhaust means for the cylinders. 45 50

13. A portable rubbing or polishing machine having, in combination, a body, two single-acting cylinders rigidly secured together at their adjacent ends and slidably supported by the body, the closed ends of 55 said cylinders being adjacent each other, pistons within said cylinders and secured to the opposite ends of the body, means for controlling the flow of pressure-fluid to and from the cylinders, a rubbing element, 60 and means rigidly connecting the rubbing element to the cylinders, said connecting means extending through an opening in the body and serving to prevent relative rotation between the body and the cylinders. 65

In testimony whereof, I have hereunto set my hand.

GUSTAF H. EKSTROM.
